UNITED STATES PATENT OFFICE.

JOHN J. ALLISON, JR., AND JESSE JACKS, OF CHANDLER, ARIZONA.

PISTON-RING TOOL.

Application filed January 13, 1926. Serial No. 81,090.

This invention relates to piston ring compressing tools and has for its primary object the provision, in a manner as hereinafter set forth, of a tool adapted to be extended upwardly through the open underside of an automobile engine crank case, to compress the ring about a piston so that the piston may be replaced in its cylinder through the crank case.

It is well known that connecting rods, connecting rod bearings and wrist pins may be replaced from the underside of an engine crank case, without removing the engine head. This work is often done in hurry-up jobs and when the work is done in this manner, the piston is drawn downwardly far enough out of the lower end of this cylinder to enable the operator to reach the wrist pin but without allowing the upper rings to leave the cylinder. The lower ring of the piston, however, slips out of the cylinder and unless the operator has the proper tool to compress this ring when replacing the piston, the ring is broken off and removed and the piston replaced in the cylinder minus the lower ring. When this is done loss of compression and oil pumping results.

The tool embodying this invention contemplates the provision of a pair of substantially semi-circular jaw members each carrying at one end an arm or handle, these handles being crossed and pivotally secured together to hold the jaw members in opposed relation. The handles where they are attached to the jaw members extend outwardly therefrom at an oblique angle with respect to the side of the jaws so that the jaws may be brought together about a piston ring to compress the same without having the handles of the compressor in the way of the connecting rod and crank shaft. In this manner the lower ring may be compressed and the piston replaced in the cylinder with all of its rings intact, instead of removing the lower ring and replacing the piston minus one ring as is the usual custom.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features

of the invention as expressed in the appended claims.

In the drawing:

Figure 1 shows the tool embodying this invention in side elevation and as gripping the lower ring of a piston.

Figure 2 shows the tool in elevation, and

Figure 3 shows a top plan view of the tool in position about a piston and ring.

Referring now to the drawing in detail wherein like numerals of reference indicate corresponding parts throughout the several views, there is indicated by the numeral 1 a portion of an engine cylinder shown in vertical section, with a piston 2 positioned in the lower portion thereof and having connected thereto the usual connecting rod 3. The usual piston rings are indicated by the numeral 4.

The implement embodying this invention comprises a pair of substantially semi-circular jaw members 5, one end of each of the jaw members being curved back upon itself to provide a loop or eye as indicated at 6.

Associated with each of the jaw members 5 is a handle member, each being indicated by the numeral 7. Each of these handle members 7 comprises an inner elongated holding portion 8, an outer offset portion 9 and an intermediate angularly disposed portion 10 which provides for the offsetting of the portion 9 relative to the portion 8. The portions 10 are flat, extend across, and are pivotally connected together by means of the pivot member 11.

The free end of each outer portion 9 is bent at an obtuse angle with respect to the remaining part of said portion, and the said obtuse angular portion is indicated at 12 and fitted into the eye or loop 6 of the jaw member 5, as shown in Figure 3. A securing material such as solder is then employed to secure the ends 12 in the loops or eyes 6 of the jaws as indicated at 13, or these jaw ends may be welded in the ends 12 of the handle member as desired. It will be seen that after affixing the crossed handles 7 to the ends of the jaw members 5 in the manner shown and explained, that the concave faces of the jaws 5 will be held in opposed relation and thus the handle member will be extended at an acute angle with respect to the side faces of the jaws 5.

This particular angle at which the handles are secured to the jaw members 5 enables the jaws to be extended upwardly through

the open bottom of the crank case, to grip and compress a piston ring into its groove in the piston 2, to enable the mechanic to re-insert the piston in its cylinder, without having the handles of the ring gripper in the way of the connecting rod and crank shaft of the engine.

From the foregoing description it will be readily seen that there has been provided a new and unique piston ring compressing tool, by means of which a ring may be easily compressed for the quick and easy replacement of a piston in this cylinder.

Having thus described our invention, what we claim is:

1. A piston ring compressing tool of the character described, comprising a pair of opposed substantially semi-circular resilient jaws, each at one end bent upon itself to form a loop, each eye being laterally offset from the jaw at its outer face, a pair of crossed pivotally connected handles, and there being obtuse angled portions bent from said handles at one end of the same and disposed at corresponding angles to each

other and engaged in the looped ends of the jaws, said handles extending at an acute angle from the plane of the lower edges of said jaws, the jaws being free of each other at their other ends remote from the loops.

2. A piston ring compressing tool comprising a pair of opposed substantially semi-circular resilient jaws, each at one end being outturned upon itself, a pair of crossed pivotally connected handles, each of said handles having its outer portion offset with respect to the remaining part thereof, and said offset portions having the outer parts thereof disposed at an obtuse angle with respect to the inner parts thereof and with said outer parts arranged at corresponding angles and secured to the outturned ends of said jaws, said jaws being free of each other at their other ends remote from the outturned ends.

In testimony whereof, we affix our signatures hereto.

JOHN J. ALLISON, JR.
JESSE JACKS.
